Fig. 2.
ON 2-2, FIG. 1.

UNITED STATES PATENT OFFICE.

AUGUST D. KUMPF, OF PHILADELPHIA, PENNSYLVANIA.

ACTUATING MECHANISM FOR WINDOWS, SASHES, SHUTTERS, OR THE LIKE.

1,337,776.

Specification of Letters Patent. Patented Apr. 20, 1920.

Application filed August 28, 1919. Serial No. 320,511.

To all whom it may concern:

Be it known that I, AUGUST D. KUMPF, a citizen of the United States, residing in the city and county of Philadelphia, State of Pennsylvania, have invented a new and useful Actuating Mechanism for Windows, Sashes, Shutters, or the like.

My invention consists of a novel construction of an actuating mechanism for windows, sashes, shutters, or the like, of that character which are customarily pivoted or hinged at their upper portions to the wall of the store, factory or other building.

Shutters of this general character are frequently heavy and cumbersome and consequently difficult to manipulate or to open and close, and my present invention comprises a novel mechanism for enabling one or more shutters of this general character to be readily opened and closed by manually operated mechanism controlled by a single operator whereby the opening and closing of the shutters or their retention in intermediate positions can be readily and expeditiously effected.

To the above ends, my invention consists of a novel construction of toggle mechanisms and their adjuncts, comprising levers collocated with a pair of sprocket chains or the like connected by suitable cross-heads, each of said cross-heads having actuating mechanism connected therewith, so that upon actuating a carrier composed of said cross-heads and chains in a desired direction, the shutter, sash or the like can be expeditiously raised and lowered, or opened and closed or retained in intermediate positions according to requirements.

It further consists of a novel construction of toggle levers and means for actuating them.

It further consists of a novel construction of actuating mechanism comprising an elongated threaded stem or screw splined to a suitable support, in conjunction with means for actuating said screw, so as to effect the operation of the toggle mechanism, whereby the shutters are actuated in the desired direction.

It further consists of other novel features of construction, all as will be hereinafter fully set forth and pointed out in the claims.

For the purpose of illustrating my invention, I have shown in the accompanying drawings one form thereof which is at present preferred by me, since the same will be

found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a vertical sectional view of an actuating mechanism for windows, sashes, shutters, or the like, embodying my invention, certain of the parts being shown in elevation, and the section being taken on line 1—1 Fig. 2.

Fig. 2 represents a section on line 2—2 Fig. 1, on an enlarged scale, showing the shutter in open position and the toggle mechanisms and their adjuncts also in open position.

Fig. 3 represents a sectional view similar to Fig. 2, but showing the shutter in closed position and the toggle mechanisms and their adjuncts also in closed position.

Fig. 4 represents a section on line 4—4 Fig. 3.

Fig. 5 represents a section on line 5—5 Fig. 4.

Fig. 6 represents a side elevation showing a portion of the connection seen at the right of Figs. 2 and 3 as composed of fusible material.

Similar numerals of reference indicate corresponding parts in the figures.

Referring to the drawings:—

1 designates the window, sash or shutter to be actuated or operated, the same being hinged or pivoted at its top or upper end 2 to the window frame 3 of the store, factory or other building. At various points I attach to the inner face of the shutter or the like 1, my novel shutter operating or actuating mechanism 4, which will now be described in detail, it being apparent from Figs. 2 and 3 that I have shown two shutter 100 actuating mechanisms employed, but it will be apparent that if desired this number can be increased or diminished. The mechanism 4 comprises two cross heads 5 and 6, which are joined by the preferably parallel 105 sprocket chains 7 and 8, whose terminals are secured to said cross-heads in any suitable manner, thereby forming a carrier or actuator for the toggle mechanism.

9 designates a vertical pillar, post or I beam within the building to which the shutter 1 is pivoted, said I beam having the

bracket 10 secured thereto in any suitable manner, said bracket having pivotally secured thereto, the bell crank or elbow lever 11, comprising the long arm 12 and the short arm 13, said arms being preferably integral, angularly arranged and pivoted to the bracket 10 at the point 14. The short arm 13 is secured to the sprocket chain 7 at the point 15, by a bolt and nut or the like, while 10 the outer end of the long arm 12, has one end of the link 16 pivoted thereto at 17, the other end of said link 16 being pivoted at 18 to the shutter 1.

The I beam 9, has a bracket 19 secured 15 thereto preferably at a point opposite to the bracket 10, to which is pivoted at 20, the extension 21 of the angular lever 22, the latter comprising the short arm 23 and the long arm 24. The short arm 23 is connected at 20 25 by any suitable means to the sprocket chain 8, while the long arm 24 is pivotally connected at 26 to one end of the link 27, whose other end is pivotally connected at 28 to the interior of the shutter 1, it being 25 seen that the levers 11 and 12 when assembled and correlated with their links 16 and 27, the sprocket chains and their supporting brackets form a toggle mechanism or system of toggle levers, which when a 30 pull is exerted on said chains in the proper direction, will cause the shutter 1 to move from the position seen in Fig. 2 to that indicated in Fig. 3.

For heavy shutters and the like, I preferably employ a second set of toggle levers as 35 29 and 30, which are supported upon brackets 31 and 32, respectively, carried by the vertical post or I beam 33, as will be understood from the left of Figs. 2 and 3, 40 and as the construction and manner of assembling the toggle levers 29 and 30 is the same as those already described and seen at the right of Figs. 2 and 3, I deem it unnecessary to describe them in detail.

45 It will be evident from Fig. 2 that a pull on the cross-head 6 in the direction of the arrow *a*, will cause the shutter 1, the toggle levers and their adjuncts to move from the open position seen in Figs. 1 and 2 to the 50 closed position seen in Fig. 3 and that a pull in the opposite direction upon the cross-head 5 will move the parts from the closed position seen in Fig. 3 to the open position seen in Fig. 2. The desired actuation of 55 the cross-heads 5 and 6 and their chains 7 and 8 may be obtained in various ways but I preferably employ the construction now to be described.

To the cross-head 5 I attach one end of 60 the connection 34, which passes over the pulley 35 rotatably mounted in a hanger 36, the other end thereof, being connected to the rod 37, whose opposite end 38 is swiveled or secured by a nut 39 or the like to the 65 elongated screw or threaded stem 40, which

is provided with the longitudinal groove 41, whose walls are engaged by the guide 42 (see Figs. 4 and 5) which is supported by, or forms a part of the bracket 43, whereby said screw is thus splined upon said bracket 70 and capable of a longitudinal movement only thereon, and no rotary movement, relative thereto. The cross-head 6 has one end of the chain or other connection 44 connected thereto, the other end of said chain passing 75 over the pulley 45 and being connected at 46 to the screw or threaded stem 40, as will be indicated from the left hand portion of Fig. 4.

47 designates an internally threaded 80 sleeve, which is pinned or otherwise secured to the sleeve or extension 48 of the worm gear 49, which is actuated by the worm 50, it being apparent that the worm gear 49 and the internally threaded sleeve 47 rotate as 85 a unit, said sleeve rotating in the bearings 51. The worm 50 can be rotated in any suitable manner as manually or otherwise and it will be apparent that the rotation of the worm gear 49 and sleeve 47, will cause 90 the elongated screw or threaded stem 40 to travel longitudinally in the desired direction and thus impart a pull or a movement in the desired direction to the connections 44, 37, and 34, thereby actuating in the desired direction the cross-heads 5 and 6 and their sprocket chains 7 and 8.

It is obvious that the gear 49 and the internally threaded sleeve 47 can be held from longitudinal movement by any suitable 100 means, as by the enlargement 54 shown in Fig. 4, but omitted from Figs. 2 and 3, which is retained between the bearings 51. The connection 34 may be constructed of fusible material as indicated at the point 52, 105 (see Fig. 6) so that in case of fire, when the shutter or shutters 1 are open as seen in Fig. 2, said fusible portion will melt, and the weight of said shutter will cause it to assume the closed position seen in Fig. 3.

110 The operation is as follows:—

When the parts are in the position seen in Fig. 3, it will be apparent that the shutter, sash, window or the like 1 stands in substantially a vertical position, and when it is desired to open the same or to actuate the shutter so that it will appear in inclined or open position as seen in Fig. 1, it is only necessary for the operator to rotate the worm 50, which can be done manually or by the 115 application of power to the wheel or pulley 53, whereupon the worm gear 49 will rotate and the sleeve 47 will also be rotated in unison therewith, whereby by reason of the threaded connection with the elongated feed 120 screw (see Fig. 4,) it will be apparent that the actuator composed of the sprocket chains 7, 8 and the cross-heads 5 and 6 will be moved to the right of the position seen in Fig. 3, 125 into the position seen in Fig. 2, whereupon 130

the shutter 1 will be raised into the position seen in Figs. 1 and 2 or into any intermediate positions desired.

When it is desired to close the shutter, the worm 50 and the worm gear 49 are actuated in the opposite direction and the parts move from the position seen in Figs. 1 and 2 to the position seen in Fig. 3.

It will be apparent that by the employment of the elongated screw 40 and its adjuncts, whereby the connections are had with the toggle mechanism, that the movement or opening and closing of the shutter or shutters will be regular and uniform and the shutter or shutters can be held in any intermediate positions desired.

It will be further apparent that my invention is applicable to shutters of any size or weight and that any desired number of shutters can be operated uniformly and synchronously.

It will be apparent that other mechanisms in lieu of the cross-heads 5, 6 and the parallel connecting sprocket chains 7 and 8 may be employed with equal facility, and I do not desire therefore to be restricted to the precise mechanism I have herein shown and described.

Having thus described my invention, what I claim as new and desire to secure by Letters Patent, is:—

1. In a device of the character stated, the combination of a shutter, toggle mechanism therefor, an actuator composed of parallel connections and cross-heads and having portions of said toggle mechanism connected to said parallel portions and mounted intermediate the latter, and means for moving said actuator in either direction with the said connections in parallelism.

2. In a device of the character stated, an actuator composed of a plurality of parallel chains, cross-heads connecting the ends of said chains, toggle mechanism including a plurality of levers having long and short arms, the short arm of each lever being connected to its respective chain, a shutter, links connecting the long arms of said levers to said shutter, and means for actuating said chains and cross-heads in either direction with the said connections in parallelism.

3. In a device of the character stated, a shutter, a pair of toggle levers pivoted to a suitable fixed support, each of said toggle levers comprising a long and short arm, links common to said long arms and said shutter, an actuator embodying cross-heads and sprocket chains connecting the same, and connections from the short arms of the respective chains of said levers to said actuator.

4. In a device of the character stated, a shutter, a pair of toggle levers pivoted to a suitable fixed support, each of said toggle levers comprising a long and short arm, links

common to said long arms and said shutter, an actuator embodying cross-heads and sprocket chains connecting the same, connections from the short arm of said levers to the respective chains of said actuator, and means for moving said actuator in either direction.

5. In a device of the character stated, a shutter, a pair of toggle levers pivoted to a suitable fixed support, each of said toggle levers comprising a long and short arm, links common to said long arms and said shutter, an actuator embodying cross-heads and sprocket chains connecting the same, connections from the short arm of said levers to the respective chains of said actuator, an elongated feed screw splined in a support, connections from each end of said feed screw to said cross-heads, and means for actuating said feed screw in either direction.

6. In a device of the character stated, a shutter, a pair of toggle levers pivoted to a suitable fixed support, each of said toggle levers comprising a long and short arm, links common to said long arms and said shutter, an actuator embodying cross-heads and sprocket chains connecting the same, connections from the short arm of said levers to the respective chains of said actuator, an elongated feed screw splined in its support, connections from each end of said feed screw to said cross-heads, means for actuating said feed screw in either direction, said means comprising an elongated interiorly threaded sleeve engaging said feed screw, a worm gear connected to said sleeve, and a worm for actuating said worm gear.

7. In a device of the character stated, the combination of a shutter, toggle mechanism for opening and closing said shutter an actuator composed of parallel connections and cross-heads therefor, and having portions of said toggle mechanism connected thereto, means for moving said actuator, and connections from each of said cross-heads to said actuator moving means and embodying a rod extended parallel with said parallel connections with one end swiveled, a portion of one of said connections being fusible.

8. In a device of the character stated, a shutter, cross-heads and sprocket chains connected thereto and forming an actuator, means connected with said cross-heads, a rod connected with the said means at one end of the actuator, a screw-threaded stem having swiveled connection with one end of said stem, said stem having a longitudinal groove, and a relatively fixed guide engaged in said groove, the said stem being connected with the means connected with the adjacent cross-heads.

AUGUST D. KUMPF.
